UNITED STATES PATENT OFFICE

2,536,475

DEVICE FOR PUMPING OUT FLOATS

John V. Thomas, Los Angeles, Calif.

Application April 2, 1947, Serial No. 738,963

1 Claim. (Cl. 103—70)

1 My invention relates to a device for pumping floats or floating docks in tidal waters. Most floating docks are constructed of wooden tanks and these tanks always leak or sweat, so as to partially fill the interior of the float. The result is that they must be periodically pumped dry. The water on the interior soaks into the wood, increasing the weight of the float, necessitating larger floats to support the same load. It is, therefore, an object of my invention to provide a device operated by the motion of the tide to pump the water from the interior of a floating dock and to keep the same empty.

Other objects and advantages of my invention will be apparent from the following description of the preferred embodiments therein.

In the drawings:

Figure 1 is a side elevation, partially sectioned; Figure 2 is a cross-section, taken on the line 2—2 of Figure 1; and

Figure 3 is a side elevation of a modification. Referring to the drawings, an ordinary wooden float dock is represented, which has wooden floats 2 for supporting the same above the surface of the water 3. A concrete pillar 4, embedded in the floor 5 of the body of water 3, maintains the floating dock 1 in position by means of rollers 6, attached to the floating dock 1. These rollers 6 allow the dock to move up and down upon the pillar 4, but prevent lateral movement.

Attached to the pillar 4 is a static line 7 of rope, cable, or other suitable material, which is anchored to the floor 5 by a weight 8. The static line 7 is held in a taut condition by the weight 8, but it makes several loops, as shown at 9, around a windlass 10. The windlass 10 is rotatably journaled upon the floating dock 1 and has thereon an off-center crank 11, to which is fastened a crank arm 12. The crank arm 12 is connected to the piston rod 13 of an ordinary diaphragm pump 14. The diaphragm pump 14 has a pipe 15 extending from the pump to the interior of the floats 2, with a check valve 16 positioned at any point in the pipe 15. This check valve 16 is of a type which will allow a flow of fluid from the float 2 to the interior of the diaphragm pump 14, but will close itself and block any flow immediately upon the application of any pressure tending to force liquid from the diaphragm pump 14 to the float 2. Another pipe 17 is connected to the top of the fluid pump 14 and opens into the water 3 at any desirable position. In this pipe 17 is a second check valve 18, which is open when there is pressure in the pipe 17 from the pump 14,

but which is immediately closed upon any back pressure.

The operation of my device is as follows: When the floating dock 1 rises and falls with the tide, the static line 7 will cause the windlass 10 to rotate, causing an up-and-down movement of the diaphragm 19 of the diaphragm pump 14. The static line 7 will cause the windlass 10 to rotate and on the downward stroke of the diaphragm 19, a suction will be placed on the pipe 15, sucking water from the bottom of the float 2. After the crank 12 has passed the center position, upon its movement around the windlass 10, the diaphragm 19 will then move upward, causing a back pressure in the pipe 15, closing the check valve 16 and the water previously sucked from the float will be forced outwardly through the pipe 17 and into the water 3. Further movement of the windlass 10 will reverse the stroke, causing a suction on the check valve 18, closing the same, and a suction on the check valve 16, opening the same.

One of the features of my invention is that, by the use of a rotating drum, such as the windlass 25 10 to operate the diaphragm pump 14, a plurality of pumping strokes is given to the pump during each rise and each fall of the tide.

In Figure 3, is shown a modification of my invention. In this device, the static line 7 is not used; but a drum, such as 20, is journaled upon a hanger 21, attached to the floating dock 1, a spring 22 places a tension upon the drum 20, causing the exterior surface of the same to engage the pillar 4, thus the rise and fall of the tide will cause the drum 20 to be rotated by its friction with the static pillar 4. This drum 20 is connected by the same cranks as the windlass 10 to the diaphragm pump 14.

One of the main features of my invention is 40 to provide a device which will cause the pump 14 to make several strokes to each rise and fall of the tide and any device, affixed in position against which a drum or static line is used, would accomplish this multiple-stroke action.

45 While I have described the preferred embodiments of my invention, I am not limited to any of the details herein set forth, except as described in the following claim.

I claim:

50 In a device for pumping seepage water out of a float, a pump having a piston, said pump being rigidly attached to said float and connected to the interior of said float, an outlet means to empty said pump, check valve means to permit the flow of liquid therethrough in one direction

only, a rotatable drum having a crank mounted thereon off center to the rotation of said drum, said crank being connected to said piston of said pump, and an anchored static line wound around said drum, said pump being rigidly affixed to the float whereby the rise and fall of said float due to the action of the tide upon said float will cause said static line to rotate said drum and actuate said pump.

JOHN V. THOMAS.
